UNITED STATES PATENT OFFICE.

FRANK DUMBOVICH, OF DETROIT, MICHIGAN.

SPARK PLUG.

Application filed May 19, 1924. Serial No. 714,387.

To all whom it may concern:

Be it known that I, FRANK DUMBOVICH, a citizen of Austria, residing at Detroit, in the county of Wayne and State of Michigan, 5 have invented certain new and useful Improvements in Spark Plugs, of which the following is a specification, reference being had therein to the accompanying drawings.

This invention has reference to spark 10 plugs for internal combustion engines and has for its object to minimize the trouble often experienced in the usual form of spark plugs from damage or undesirable variations in the setting of the firing or sparking 15 points due to the heat and force of cylinder explosions.

It is also an object to provide an easily 20 constructed form of plug wherein a permanent firing element is provided together with a removable and renewable element; and it is still further an object to provide 25 in such a device, for the adjustment of such renewable element with respect to the firing element.

30 A still further object is to provide firing elements of said type of robust construction particularly adapted to withstand the force and heat of explosions; and still further objects subsidiary to or resulting from the 35 aforesaid objects or from the construction or operation of the invention as it may be carried into effect, will become apparent as the said invention is hereinafter further disclosed.

35 In carrying said invention into effect I may provide a spark plug shell such as of any well known type having extending from its inner end one or more arms supporting a firing member, in the front plate or disk 40 in a plane transverse to the said shell and substantially spaced therefrom, the said disk having sharp projections or points on its inner face and the said shell being provided with the usual insulator and central insulated conductor, to the inner end of which 45 is secured a second firing member having arms the extremities of which terminate at a desirable distance from the points on the inner side of the said plate. This latter

50 firing member is preferably detachable from the plug either with the said conductor or from the said conductor and adjustable with respect to the said plate whereby the distance between the plate and the adjustable 55 firing member may be varied to suit the circumstances under which the plug is to be

used. All of which is more particularly described and ascertained hereinafter, by way of example, having reference to the accompanying drawing, wherein— 60

Figure 1 is an elevation, with parts broken away and shown in section, of a spark plug embodying the said invention;

Figure 2 is a fragmentary detail view of the lower parts of the same, also partly 65 broken away and illustrated in section at right angles to that in Figure 1;

Figure 3 is a sectional plan detail of the firing element;

Figure 4 is a broken perspective view of 70 the fixed firing element, and

Figure 5 is a similar view to Figure 2 illustrating a modified form of the invention.

Similar characters of reference indicate 75 similar parts, in the several figures of the drawing.

1 is the tubular threaded shell of a spark plug enclosing an insulator 2 through the center of which passes a conductor 3, and 80 4 is a firing element in the form of a plate or disk integrally connected to and spaced from the lower open end of the said shell 1 by arms 5, the spacing of the said firing member 4 from the end of the shell being 85 sufficient to permit of free circulation of gases around the said firing member when the spark plug is in use.

At the lower extremity of the conductor 3 is secured a second firing element 6 which is 90 shown as being in the form of a bent strip having a pair of arms 7 provided at their extremities with lateral projections 8, whereby said arms are of an inverted T-shaped configuration, the transverse heads 95 of which arms lie in approximately parallel relation to the firing member 4 and may be set at an effective firing space therefrom whereby sparks may pass between the said plate and any part of the inverted T heads 100 of the said firing member 5. To increase the effectiveness of the device I prefer to provide the firing member 4 with a plurality of upwardly extending projections or points 105 as indicated in Figures 1, 2 and 3.

In Figure 5 the lower end of the connector 3 is shown as being threaded and provided with adjustable nuts 10 and 11 between which the firing member 6 is secured and by means of which said firing member may be 110 adjusted with respect to the firing member 4, which in this case is shown as having a

central orifice 12 therein to permit access to the nuts by means of a suitable tool for the purpose of effecting their adjustment.

It will be seen that the said firing member 5 may be readily removed and replaced if required, in the case of the arrangement shown in Figure 5 by its detachment from the end of the conductor 3 and in the case of Figure 1 by the withdrawal of the conductor 10 from the insulator 2 after its removal from the shell.

The arrangements described are very simple in construction and capable of being made very rigid to withstand hard usage, 15 the fixed firing member 4 being of a particularly robust nature and acting as a protecting shield for the firing element 6 whereby the force of explosion does not tend to bend or otherwise alter the spaced adjustment 20 of the two firing members.

This invention may be developed within the scope of the following claims without departing from the essential features of the said invention and it is desired that the 25 specification and drawing be read as being merely illustrative and not in a limiting sense except as necessitated by the prior art.

What I claim is:—

1. In a device of the class described, a 30 firing member in the form of a plate, and a further firing member having downwardly projecting arms provided with lateral projections extending approximately parallel to said plate.

2. In a device of the class described, a 35 firing member in the form of a plate provided with upwardly projecting points, and a further firing member having downwardly projecting arms provided with lateral projections at their extremities extending 40 approximately parallel to said plate.

3. In a device of the class described, a 45 firing member in the form of a plate provided with upwardly projecting points, and a further firing member having downwardly projecting arms provided with lateral projections at their extremities terminating in proximity to the points on said plate.

4. In a device of the class described, a 50 shell, an insulator therein, a conductor passing through said insulator, a firing member on the inner end of said conductor and a further firing member spaced from the inner end of said shell and extending protectively over and in spaced relation to said 55 first mentioned firing member.

5. In a device of the class described, a 60 firing member in the form of a plate, and a further firing member having inverted T-shaped arms the heads of which terminate in proximity to said plate.

In testimony whereof I affix my signature in presence of two witnesses.

FRANK DUMBOVICH.
